UNITED STATES PATENT OFFICE

148,964

DESIGN FOR A SHOE

Isidor Tarlow, Brockton, Mass.

Application March 28, 1947, Serial No. 137,994

Term of patent 7 years

(Cl. D7—7)

To all whom it may concern:

Be it known that I, Isidor Tarlow, a citizen of the United States, residing at Brockton, in the county of Plymouth and Commonwealth of Massachusetts, have invented a new, original, and ornamental Design for Shoe, of which the following is a specification, reference being had to the accompanying drawing, forming part thereof.

The figure is a side perspective view of a shoe showing my new design, the opposite side presenting substantially the same appearance as the side shown.

The principal features of applicant's design consist in the scalloped or wave-like seam extending around the shoe upper and exhibiting an irregular line of demarcation between vamp areas of contrasting texture, in a shoe of the type shown in the drawing.

I claim:

The ornamental design for a shoe, substantially as shown and described.

ISIDOR TARLOW.
